UNITED STATES PATENT OFFICE.

CHARLES MAWER, OF BUCYRUS, OHIO.

SIGNAL-LAMP.

1,178,742.

Specification of Letters Patent. Patented Apr. 11, 1916.

Application filed January 29, 1915. Serial No. 5,064.

To all whom it may concern:

Be it known that I, CHARLES MAWER, a citizen of the United States, residing at Bucyrus, in the county of Crawford and 5 State of Ohio, have invented new and useful Improvements in Signal-Lamps, of which the following is a specification.

This invention relates to signal lamps and more particularly to a combined lamp 10 and license plate holder, and has for its primary object to so construct and arrange the parts that they can be readily disassembled for various purposes.

Another object of the invention is to so 15 form the parts that they can be readily stamped into their various formations.

With these and other objects in view, the invention consists of the novel features, details of construction and combination of 20 parts, which hereinafter will be more particularly set forth, illustrated and claimed.

In the accompanying drawings:—Figure 1 is a front view of the lamp. Fig. 2 is a cross section therethrough. Fig. 3 is a longitudinal section therethrough. Fig. 4 is an enlarged detail section. Fig. 5 is a rear elevation of the lamp.

Referring to the drawings the numeral 1 designates a casing tapering in a forward 30 direction and as shown has connected to its rear portion a pair of spaced ears 2 adapted to receive the spaced arms 3 of a bracket 4. The rear of the casing is provided with a circular opening 5 in which is fixed the 35 socket 6 of an electric light 7. Detachably positioned interiorly of the casing through the medium of resilient fingers 8 bent inwardly from the casing is an outwardly diverging reflector 9. This reflector 9 is also 40 provided with an opening 10 in alignment with the opening 5, and as shown the walls thereof encircle the base portion of the bulb 11 of the light. By this structure it will be seen that the rear face of the reflector abuts the lamp socket 6 so as to limit 45 the rearward movement of the reflector, the fingers 8 limiting when in an operative po-

sition the forward movement of the reflector. Hingedly connected to the edge of the casing is a door frame 12 L-shaped in cross- 50 section. Abutting the vertical portion of the door frame is a number plate 13, which in turn has its rear surface in close contact with a colored transparent plate 14.

I provide resilient means such as leaf 55 springs 15 for yieldably holding the colored plate and number plate in close contact with the vertical portion of the door frame. Each of the leaf springs 15 has one extremity secured to the horizontal portion 16 of 60 the door frame.

By constructing a lamp as shown, I can readily remove the reflector from the casing by depressing the fingers 8 toward the casing, thus allowing the reflector to slide toward the open end of the casing, it being understood that prior to this the bulb 11 has been removed from the lamp socket 6. When the upper edges of the plates 13 and 65 14 are forced rearwardly the resiliency of 70 the springs allows the rear portions of the plates to be dislocated from between the leaf springs 6 and the inner surface of the door frame.

Having thus described my invention, 75 what I claim as new is:—

A signal lamp comprising a casing having its edge bent at right angles, a cover secured to the right angular bent edge, said casing having instruck resilient fingers, a 80 reflector having its edge portion abutting said fingers, and illuminating means passing through said reflector and casing, said fingers limiting movement of the reflector in one direction while said means limits the 85 movement of said reflector in an opposite direction.

In testimony whereof I affix my signature in presence of two witnesses.

CHARLES MAWER.
